(57) **CLAIM**

The ornamental design for an industrial robot, as shown and described.

DESCRIPTION

FIG. 1 is a front-right-top perspective view of an industrial robot showing our new design;

FIG. 2 is a rear-left-bottom perspective view thereof;

FIG. 3 is a rear-right-top perspective view thereof;

FIG. 4 is a front-left-bottom perspective view thereof;

FIG. 5 is a right side view thereof;

FIG. 6 is a left side view thereof;

FIG. 7 is a top plan view thereof;

FIG. 8 is a bottom view thereof;

FIG. 9 is a rear view thereof;

FIG. 10 is a front view thereof; and

FIG. 11 is an enlarged view directed to the portion identified by region **11-11** of FIG. 1;

FIG. 12 is an enlarged view directed to the portion identified by region **12-12** of FIG. 2; showing a portion in **12-12** of FIG. 2;

FIG. 13 is an enlarged view directed to the portion identified by region **13-13** of FIG. 5;

FIG. 14 is an enlarged view directed to the portion identified by region **14-14** of FIG. 6;

FIG. 15 is an enlarged view directed to the portion identified by region **15-15** of FIG. 7;

FIG. 16 is an enlarged view directed to the portion identified by region **16-16** of FIG. 8;

FIG. 17 is an enlarged view directed to the portion identified by region **17-17** of FIG. 9; and,

FIG. 18 is an enlarged view directed to the portion identified by region **18-18** of FIG. 10.

The broken line showing of the remainder of the industrial robot represents portions which form no part of the claimed design.

1 Claim, 18 Drawing Sheets
